SOUND RECORDING

Josef Mayer, Berlin-Lankwitz, Germany, assignor
to Tobis, Tonbild-Syndikat A. G., Berlin, Ger-
many, a corporation of Germany

Application February 11, 1937, Serial No. 125,195
In Germany October 24, 1935

2 Claims. (Cl. 179—100.3)

This invention relates to the production of sound records, such as those utilized in conjunction with motion pictures, and has for its principal object the provision of an improved and relatively inexpensive sound recording apparatus and method of operation whereby a variable density record of either the class-A or class-B type may be produced.

As used in the following description and claims, 10 the term class-A is intended to designate a sound record including two similar sound tracks displaced in phase by 180° and the term class-B is intended to designate a sound record including two sound tracks, on one of which is recorded the 15 positive half cycles of the sound wave and on the other of which is recorded the negative half cycle of the sound wave. The class-A and class-B types of records are both classed as push-pull records.

20 As disclosed by U. S. Patent 1,833,373, a class-A variable density type of push-pull record may be produced by means of two glow lamps which have their illumination modulated by similar sound waves displaced in phase from one another 25 by 180°. It has also been proposed to produce a class-A variable area type of push-pull record by means of a sound wave controlled galvonometer arranged to vibrate a beam of light lengthwise of a light slit so that the edges of the beam 30 never pass beyond the ends of the slit. The present invention is distinguished from these two different arrangements in that a light beam of constant intensity is applied to the reflector of 35 a sound wave or audio current controlled galvonometer either (1) through light wedge elements which have their transparency gradually varied in opposite directions or (2) through light wedge elements which have their transparency 40 gradually varied for one half cycle of the recorded sound wave and have a constant transparency for the opposite half cycle of this wave. As will appear, the use of the first type of light wedge 45 results in a class-A type of push-pull record, the use of the second type of wedge results in a class-B type of push-pull record, and these two types of light wedges are arranged to be interchanged for producing the different types of 50 push-pull records.

The invention will be better understood from the following description when considered in connection with the accompanying drawing and its scope is indicated by the appended claims.

55 Referring to the drawing

Fig. 1 illustrates a sound recorder embodying the invention.

Fig. 2 illustrates a type of light wedge suitable for producing a class-A type of push-pull record.

Fig. 3 illustrates a type of light wedge suitable for producing a class-B type of push-pull record.

Fig. 4 is an explanatory diagram relating to the negative record produced by the light wedge of Fig. 3, and

Fig. 5 is a similar diagram relating to a positive record made from such a negative.

Fig. 1 shows a constant light source 1, a condenser lens 2 which concentrates the light of the source 1, and projects it through the two light openings 4 and 5 by means of lens 6 on mirror 7. 15 This mirror is movable around an axis, crossing the running direction of the film vertically, and is controlled by the oscillations to be recorded. In diaphragm 3 there are inserted two light absorbing media in openings 4 and 5, e. g. grey 20 wedges. These wedges are mounted in such a way that one has an increasing transparency from the top to the bottom, the other an increasing transparency from the bottom to the top. By means of lens 9 mirror 7 throws two images 25 4' and 5' of the two grey wedges that are in openings 4 and 5 on slot diaphragm 10. The position of the two images 4' and 5' in relation to slot 11 is of such a nature that one half length 30 each of the slot is supplied with light by one grey 35 wedge image, and that at the position of rest of the mirror the mean transparency lies above the slot opening. The upper and lower edge of the images lie parallel to the slot length. With a rotation of mirror 7 the two grey wedge images 40 travel over slot 11, viz vertically to the slot length, and according to their position and transparency, more or less light is allowed to pass through the slot. Slot 11 is portrayed in a reduced size on film 14 by means of lens 12 at 13; it records two 45 rows of sound tracks with an opposed blackening change, viz a class-A push-pull sound record, on the film. Prism 15 is included merely for reasons of drawing technique for the purpose of illustrating better the ray course, and images 4' and 5'.

In Fig. 2, slot diaphragm 10 with slot opening 11, and images 4' and 5' of the grey wedges is illustrated. The fading transparency of the two grey wedges is indicated in their images 4' and 5' by the more or less closed hatched design. The 50 height of the two grey wedge images must, of course, be a multiple of that of the slot. In order to obtain the largest possible egress control of the light with the smallest possible motions of the mirror, the grey wedges will be designed with 55

a steeply increasing transparency, and arrangements for their equivalent portraying will be made.

The advantages of the arrangement according 5 to the invention are that only one light source, and only one controlling or light modulating element are required for recording in accordance with the variable density process. Furthermore, the controlling energy required can be kept at a 10 very small amount because the amplitudes of motion of the mirror can be maintained at a very small figure if correspondingly steep grey wedges are used. Also, the light egress control is greater than with the previous processes because it exclusively depends on the dimensioning 15 of the blackening range of the grey wedges.

The arrangement can also be employed for producing a class-B push-pull type sound record with which only the positive half-waves are recorded on one sound track, only the negative half-waves of the oscillation are recorded on the other sound track, and the blackening or transparency remains constant between the individual half-waves of each sound series. It is preferable 20 that the constant shading between the half cycles on the negative be relatively small or close to the limit of halation, and relatively large, about 25 from 1.0 to 1.2, on the positive. This affords the advantage that as a consequence of the intensive 30 blackening of the positive the ground noise caused by the granulous nature of the photographic layer can be reduced almost to the theoretically possible minimum amount, whereby a purer sound reproduction, and a greater egress control possibility, viz a pure sound effect, is produced with 35 necessity of having the additional control of the light controlling organ otherwise employed in recording. The reason of the greater egress control is that the blackening range of a half-wave 40 is no longer given by the quotient of "a maximum blackening in relation to a blackening of rest" or of "a blackening of rest in relation to a minimum blackening", but by the quotient of 45 "a maximum blackening in relation to a minimum blackening."

This half-wave recording can be effected by the fact that the grey wedges inserted into diaphragm openings 4 and 5 in Fig. 1 are made in such a way that one half has a small transparency, which is constant, according to the half-wave which is not to be recorded, while the other half shows a changeable transparency according to the half-wave to be recorded. In this case, the change from the constant transparency to the 55 changeable transparency does not follow a desultory course, but a fading course, i. e. the course of transparency of the grey wedge is of such a

nature that it first drops to a minimum, and remains constant and equal to the minimum value from that point. The optical image of such grey wedges on the slot diaphragm is shown in Fig. 3, 5 viz again for the position of rest of the mirror. 10 is the slot diaphragm, 11 the slot opening, and 4' and 5' are the images of the new grey wedges. The portion between a and b or between a' and b' corresponds to the changeable decreasing 10 transparency of the grey wedge, that between b and c or between b' and c' to transparency, remaining equal, of the grey wedge. When portion bc or $b'c'$ travels over slot 11 only a small and constant shading is recorded on the negative; in case portion ab or $a'b'$ travels over the slot, 15 a changeable shading corresponding to a half-wave of the oscillation to be recorded is recorded.

In Fig. 4, the dependence of shading S on the position of the grey wedge images in relation to the slot is represented for the two sound tracks, 20 viz for the negative. Fig. 5 shows the corresponding blackening curves of the positive.

The reproduction of this half-wave record is effected in the same way as that of a push-pull sound record. The two sound tracks are illuminated by a light slot, and the light changes of each sound track are carried to one photo-electric cell each. The sound wave halves displaced by 180° in their phase are again united by an electric push-pull connection to the full oscillation, 25 and the latter is carried to the control grid of the first amplifier tube in a well known manner.

The advantages of this novel process are that it acts as a pure sound process by itself without necessity of having the additional control of the light controlling organ otherwise required in recording. Another advantage of the process is that the shading range which is available for recording a half-wave is doubled, as compared 30 with the previous intensity processes.

I claim as my invention:

1. The combination of means for producing a light beam, means defining a light slit, means for controlling said light beam to produce at said slit images which vary inversely in light intensity transversely of said slit, and means for vibrating said images transversely of said slit.

2. The combination of a source of light, means defining a light slit, means for causing said light to appear at said slit as a pair of images which vary inversely in light intensity transversely of said slit and have opposed constant and variable light intensities longitudinally of said slit, and means for vibrating said images transversely of 55 said slit.

JOSEF MAYER.
